UNITED STATES PATENT OFFICE.

JAMES C. THOMPSON, OF SALEM, VIRGINIA.

METALLIC RAILWAY-TIE.

No. 871,049.

Specification of Letters Patent.

Patented Nov. 12, 1907.

Application filed June 1, 1907. Serial No. 376,870.

To all whom it may concern:

Be it known that I, JAMES C. THOMPSON, a citizen of the United States of America, and resident of Salem, county of Roanoke, State of Virginia, have invented 5 certain new and useful Improvements in Metallic Railway-Ties, of which the following is a full and clear specification, reference being had to the accompanying drawing, in which—

Figure 1 is a side elevation of a railway tie constructed according to my invention; Fig. 2 a plan view thereof; Fig. 3 an end elevation; and Fig. 4 a detail perspective view of a portion of the tie.

The object of this invention is to provide an improved metallic tie and track fastening device which will be durable, inexpensive, and reliable, as more fully hereinafter set forth.

Referring to the drawings by reference characters, *a* designates the tie which is approximately I-shaped in cross-section, having a central vertical web and oppositely projecting flanges at its upper as well as its lower edge, making a light and very strong structure.

The upper flanges are laterally extended where the rails rest upon the tie, forming shoulders *b* which face toward the same end of the tie. By preference I have 25 both sets of shoulders face toward the same end of the tie. On top of the tie is riveted or otherwise fastened a permanent clip *c* for each rail which is adapted to engage over the foot-flange of the rail. These permanent clips or flanges face in the same direction as the shoulders *b*.

In connection with each one of these permanent stops or flanges *c* I employ a slidable clip *d* which consists of a plate adapted to rest upon the upper side of the tie and beveled so as to engage over the adjacent foot-flange of the rail. At each side edge of this plate *d* is a depending flange *d'* which flanges lie close to the side edges of the upper flanges of the tie when the clip is in place. Each of these flanges is provided with a forwardly projecting lug *d''* which is beveled on its upper face so that when the clip is slid up toward the rail these lugs *d''* will engage under the shoulders *b* and thus tightly clamp the rail to the tie and against the opposite sta-

tionary clip *c*. These slidable clips are forced up against the rail-flange by means of a pair of wedges or keys *e* which are driven down through registering openings in the top and bottom flanges of the tie, and to prevent these keys or wedges being withdrawn after they are driven home the lower ends thereof, which project below the lower surface of the tie, are struck up or bent laterally.

It will be observed that by my invention I provide a very durable and rigid fastening means which will not require the use of any fastening bolts or other devices liable to loosen or break. I prefer having both the permanent clips face in the same direction in order that any tie may be readily removed and replaced by simply manipulating the movable fastening clips.

Having thus fully described my invention, what I claim and desire to secure by Letters Patent, is:—

1. In combination with a railway-tie having longitudinal lateral flanges along its upper edge, these flanges being provided with shoulders facing toward the same end of the tie, a rail clip fastened to the tie adjacent to each pair of shoulders and facing in the same direction as the shoulders face, a removable clamp or clip slidably mounted on the tie adjacent to each pair of shoulders, each of these clips being provided with depending flanges and forwardly projecting lugs, and means for forcing these slidable clips toward the rail and locking them in place, the said lugs being adapted to engage under the oppositely projecting shoulders of the tie.

2. In combination with a railway-tie having longitudinal flanges along its upper as well as its lower edge, the upper flanges being enlarged laterally to form endwise facing shoulders *b*, a clip adjacent to each pair of shoulders and facing in the same direction, a slidable clip on the tie adjacent to each pair of shoulders and facing in the opposite direction, each clip being provided with depending side flanges having formed on them forwardly projecting lugs adapted to engage under the oppositely projecting shoulders *b*, and vertical locking wedges or keys driven down behind each slidable clip and extending down through both flanges of the tie.

In testimony whereof I hereunto affix my signature in the presence of two witnesses this 29 day of May 1907.

JAMES C. THOMPSON.
